CLAIM

The ornamental design for storage can, as shown and described.

DESCRIPTION

FIG. 1 is a front, left, and top perspective view of a storage can, showing my new design;
FIG. 2 is a rear, left, and bottom perspective view thereof;
FIG. 3 is a front elevational view thereof;
FIG. 4 is a rear elevational view thereof;
FIG. 5 is a right elevational view thereof;
FIG. 6 is a left elevational view thereof;
FIG. 7 is a top plan view thereof;
FIG. 8 is a bottom plan view thereof;
FIG. 9 is a front, left, and top perspective view thereof when being opened; and,
FIG. 10 is a rear, left, and bottom perspective view thereof when being opened.
The brackets shown in FIG. 9 and FIG. 10 do not depict any portion of storage can and form no part of the claimed design.

1 Claim, 10 Drawing Sheets(56)
